AUTOMATIC LIGHTER

Stephen W. Neldner, Milwaukee, Wis.

Application November 24, 1930, Serial No. 497,765

4 Claims. (Cl. 158—115)

This invention relates to automatic lighters for gas heaters for use particularly in connection with gas stoves, ranges and ovens.

One object of the present invention is the provision of an automatic lighter which will produce an igniting flame in response to movement of a burner control element prior to the admission of gas to the burner so that ignition of the burner will be effected promptly upon admission of gas thereto.

10 Another object of the present invention is the provision of gas connections between the several burner valves and the flash lighter so that movement of any burner control element will effect the projection of a lighting flame to the several burners.

20 Another object is the provision in a gas stove having a plurality of burners, one of which is an oven burner, and a single lighter therefor of means for igniting an auxiliary jumper flame in response to movement of the oven burner valve to effect lighting of that burner from the flash lighter through the jumper flame.

25 A further object resides in the provision of novel means for effecting the flash lighting flame by initial movement of the valve handle by either axial movement or rotation thereof.

30 Another object resides in the provision of a novel and improved tip for the flash lighter.

35 Another object resides in the improved means for establishing a simmer flame by rotating a valve stem beyond the normal open position to thereby cut off a portion of the gas supply to the burner.

Other objects and advantages will appear from 40 the following description of an illustrative embodiment of the present invention.

In the accompanying drawings:

Fig. 1 is a top plan view of a conventional gas stove and oven equipped with an automatic igniting system constructed in accordance with the present invention, parts being broken away to better illustrate the operation.

45 Figure 2 is a vertical sectional view of one of the burner control valves.

Fig. 3 is a fragmentary elevational view of a portion of the operating valve taken at right angles to Fig. 2.

50 Fig. 4 is a horizontal sectional view taken on the line 2—2 of Fig. 2.

Fig. 5 is a sectional view taken on the line 5—5 of Fig. 2; the dotted line showing of the valve stem indicating the position of the ports to effect a simmer flame by continued rotation of the valve stem beyond the normal full open position.

Fig. 6 is a sectional view taken on the line 6—6 of Fig. 2.

Fig. 7 is a sectional view taken on the line 7—7 of Fig. 2.

Fig. 8 is a view partly in section and partly in elevation of the oven control valve shown in Fig. 1.

Fig. 9 is a horizontal sectional view taken on the line 9—9 of Fig. 8.

Fig. 10 is a horizontal sectional view taken on the line 10—10 of Fig. 8.

Fig. 11 is a vertical sectional view through the lighter tip and housing therefor.

Fig. 12 is a horizontal sectional view through the lighter tip and hood taken on the line 12—12 of Fig. 11.

The gas stove shown in Fig. 1 is of conventional form and includes the usual burners 10 and an oven burner 11 which are supplied from the customary gas manifold 12 through cocks 13 which differ from standard construction in a manner to be hereinafter more specifically described. The stove is also equipped with a flash lighter 14 having the general attributes of the ordinary lighter but provided with novel features to be hereinafter more specifically described. The flash lighter 14 is positioned in the usual manner between the several burners 10 and receives its gas supply through a tube 15 from the manifold 12 through appropriate gas connections to be hereinafter described in detail.

Although the valve bodies 13 are of usual design and appearance they are provided with valve stems 16 which are specially constructed to carry out the novel method of effecting ignition of the flash lighter by the initial movement of the operating handles 17 which are suitably connected to the valve stems 16 in a manner to be herein-after more specifically recited.

The gas cock shown in Figs. 2 to 7 is adapted for use in any of the stove burners 10, the remaining valves for the stove burners 10 being similar save for the fact that they are not provided with bleed ports or needle valves to maintain a pilot light in the flash lighter. The valve 13" for the oven burner 11 differs slightly from the construction of the remaining valves and is clearly illustrated in Figs. 8 to 10 inclusive in the drawings. Its construction in operation will be more clearly recited when the functioning of the system is later described.

The general assembly of the several elements is identical with present day stove assembly save for the fact that the several valves are provided with means which will automatically es-

tabish an igniting flame from the flash lighter upon initial movement of any of the valve handles 17 prior to the admission of gas to the particular burner which the valve normally regulates.

5 The valve housing 13 comprises a pair of oppositely directed nipples 18 and 19 for connection with the burners 10 and manifold 12 respectively. The housing 13 is also provided with a threaded boss 20 adapted to receive the end of a supply pipe 21. A suitable coupling nut 22 serving to anchor the pipe 21 to the boss 20 securely to prevent gas leakage. A longitudinal bore 23 in the valve housing 13 serves to receive the valve stem 16. The valve stem or plug 16 is of hollow construction and rotatable in the housing 13 to control communication between the nipples 19 and 18 and thus control the supply of gas to the burner 10. A spring 24 on one end of the stem 16 coats with the end of the housing 13 in a well known manner to maintain the tapered stem 16 snugly seated within the bore 23 of the housing 13. A usual stop pin 25 on the stem 16 is movable within a cutaway portion 26 of the valve housing 13 to limit the rotation of the stem.

25 The nipple 19 is provided with a central passage 27 which is in constant communication between the manifold 12 and a central bore 27' in the valve stem 16. A bleed passage 28 is directed from the passage 27 and communicates with a passage 29 to supply the pilot lighter 14 with sufficient gas to maintain the pilot light. The amount of gas so supplied is controlled through adjustment of a needle valve 30 within the passage 28. The passage 29 opens into a bore 31 within the boss 20, and thence is directed through the pipe 21 to the pipe 15 and thence to the lighter tip. Thus it will be noted at all times that the pilot lighter receives a supply of gas regardless of the position of any of the valve handles by virtue of the open communication with the manifold 12.

40 An auxiliary plug 32 is fitted for longitudinal movement within a reduced passage 33 which communicates with the passage 27'. The plug 32 is provided with an enlarged head 34 which forms a valve for controlling the passage of gas from the chamber 27' to the bore 33. The plug 32 is provided with a reduced portion so as to permit a flow of gas from the bore 33 through a port 36 in the valve stem so as to communicate with the annular passage 37 in the casing 13 and thence with the passage 31 in the boss 20. The plug 32 is provided with screw threading 38 at its upper extremity for the purpose of receiving a screw threaded plug 39 which is seated within a bore 40 at the upper end of the valve stem 16. A coil spring 41 which surrounds the plug 32 serves to retain the head 34 against the valve seat by virtue of the fact that it is confined between the plug 39 and the base of the bore 40. A pair of oppositely disposed slanting slots 42 are directed transversely through the upper portion of the valve stem 16. An anchoring pin 43 serves as a means for anchoring a head casting 44 onto the stem 16. The head casting 44 is provided with a central hollowed out portion 45 which is adapted to fit snugly over the upper end of the valve stem 16. The valve operating handle 17 is anchored within the head 44 by means of a cap screw 46 whose threaded end is anchored within a spherical member 47.

65 A pin 48 which passes through the head 44 of the member 47 serves to anchor the last named member against rotation within the member 44 but permits a rocking movement of the handle 17 within the head 44 upon the pin 48. The

member 47 is provided with a flat face 49 which is adapted to engage the upper extremity of a plug 50 which is positioned within the bore 40 of the valve stem 16. The plug 50 is provided with a slot 51 through which the anchoring pin 43 passes. The purpose of the slot 51 is to permit the plug 50 to be moved longitudinally upon raising or lowering the handle 17. When the handle 17 is raised or depressed the flat face 49 will force the plug 50 downwardly against the plug 39 thereby compressing the spring element 41 and disengaging the valve head 34 from its seat to thereby permit the admission of gas from the passage 27' through the passages 33, 36, 37 and 31 and thence to the supply pipe 21 to provide a charge of gas to energize the flash lighter to produce the several projecting flames for igniting the burner.

The identical result described in the preceding paragraph may be accomplished by the initial rotation of the valve operating handle 17 through the lost motion connection afforded by cooperation of the pin 43 with the slots 42. Upon rotation of the handle 17 and the head 44 the pin 43 will be forced downwardly and engage the upper face of the plug 39 to effect a depression of the same to free the valve head 34 from its seat and effect the gas connection previously referred to for the purpose of energizing the flash lighter.

It will thus be noted that the initial movement 30 of the valve operating handle 17 will serve to establish a gas connection between the manifold 12 and the lighter 14 regardless of whether the initial movement be one of rotation or axial displacement of the handle 17. Continued rotation of the handle 17 will establish communication between a port 52 in the valve stem 16 and a central passage 53 within the nipple 18. A port 54 in the valve stem 16 serves always to afford communication between the passage 27 in the 40 nipple 19 and the longitudinal bore 27' in the valve stem 16. The pipe 21 which leads from the valve 13 is connected to a boss 20' of the next successive gas cock 13'. The construction of the second gas cock being substantially identical to 45 the one just described save for the fact that a pair of diametrically opposed bosses 20' are provided instead of the single boss 20 as shown in the valve portrayed in Fig. 2. Each of these bosses communicates with the annular passage 37 in the valve body 13 through passages 31 which are similar to those shown in Figs. 2 and 5. The other respect in which the succeeding valves 55 housings 13' differ from the one previously described resides in the fact that the additional 55 housings are not provided with the bleed passage to effect a gas connection for maintaining a pilot light.

The oven cock 13" shown in Figs. 8, 9 and 10 differs from the other cocks 13 and 13' by reason 60 of the fact that no bleed passage is provided and further that passage 37 contained in the other valves has been eliminated. The oven valve is similar in all other respects with the valve shown in Fig. 2 save for construction of the valve plug 16' which is provided with a pair of ports 36' and 36" instead of the single port 36 as shown in the valve stem 16. Ports 31' and 31" contained in the bosses 20' serve to cooperate with the ports 70 36' and 36" to establish gas communication between the central bore 33' of the valve stem 16' and the pipe 21 and a pipe 55. The pipe 55 is directed inwardly and terminates in a nozzle 56 which cooperates with an aperture 57 in the 75

oven wall 58 to direct a jet of gas toward the oven burner 11.

The initial movement of the valve operating handle 17" on the cock 13" will serve to establish 5 gas communication between the passage 27" in valve stem 16' and the passage 36" which communicates with the pipe 21. This gas connection will energize the lighter and project igniting flames therefrom. Continued rotation of the 10 handle 17" will establish communication between the port 36" and the passage 31" which communicates with the pipe 55.

It will be noted from the preceding paragraph 15 that the initial movement of the operating handle 17" serves only to establish gas communication between the manifold 12 and the lighter 14 in a manner identical with that described heretofore with respect to valve 13. The continued rotation of the operating handle 17" will place the port 20 36" in communication with the port 31" so that both ports 36' and 36" are simultaneously supplying gas to their respective passages during a portion of rotation of the valve body 16'. Further rotation of the valve body 16' will cut off 25 communication between ports 36' and 31' and thus cut off the gas supply to the lighter 14. This particular sequence of operation is important by reason of the fact that initial movement of the valve handle 17" will energize the lighter 14; continued movement of the handle will supply 30 the nozzle 56 of the pipe 55 with a gas supply which is projected in the path of one of the lighter flames. When this condition exists the gas supply to the nozzle 56 will be ignited and 35 form a jumper flame to carry the lighter flame to a remote burner and to ignite the same. In this case the remote burner is the oven burner 11. Further rotation of the valve stem 16' will supply 40 gas to the oven burner 11 and upon release of the valve handle 17" the gas supply to the jumper torch will be cut off in a manner identical with the operation of the valve 13.

The novel lighter tip embodied in the present invention comprises the usual supply pipe 15 which is upwardly turned at its extremity and 45 provided with threading 21'. A nut 59 serves as a foundation upon which the lighter assembly is supported. A base plate 60 rests upon the nut 59 and is provided with a downwardly turned flange portion 61. A hood 62 preferably formed 50 of sheet metal is provided with a plurality of apertures 63 through which igniting flames may be projected. A tip 64 fashioned in the form of a nut adapted to be received on the threaded portion 21' on the pipe 15 is provided with a reduced upper extremity. A central passage 65 extends longitudinally through the nut 64. A plurality of slots 66 are cut down from the upper extremity of the reduced portion of the nut 64 55 to form gas ports. A plug 67 is adapted to close the upper extremity of the passage 65 and is longitudinally adjusted by reason of frictional engagement with the walls of the passage 65 so that the desired portion of the slots 66 may be 60 uncovered to provide the proper size jet for the igniting flame to insure its projection to the several burners 10 and also to the jumper flame nozzle 56.

The provision of the jumper flame together 65 with an igniting flame for carrying a light to a

remote burner provides great flexibility in operation of stove and oven burners by reason of the fact that it eliminates the necessity for the installation of a second lighter element within the oven in order to provide automatic lighting of 5 the oven burner upon manipulation of the oven valve cock.

While the device has been described in considerable detail in the foregoing specification, various changes may be made in the embodiment 10 of the invention hereinabove specifically described without departing from or sacrificing any of the advantages of the invention herein-after claimed.

I claim:

1. The combination of a plurality of gas burners, individual regulating valves therefor, a flash lighter for igniting said burners, an independently operable auxiliary valve associated with each of said regulating valves for controlling said lighter, a control element for each of said regulating valves effective to operate the associated auxiliary valve, and means for automatically closing each auxiliary valve upon manual release of the associated control element. 20

2. The combination of a plurality of gas burners, individual regulating valves for said burners, a flash lighter for said burners, an auxiliary valve associated with each of said regulating valves for controlling said lighter, a control element for each of said regulating valves, and an operating connection between each of said control elements and the associated auxiliary valve effective to render said lighter effective upon initial movement of said element and to render 30 said lighter ineffective upon release of said element.

3. The combination of a plurality of burners, individual regulating valves for said burners, a flash lighter for said burners, an auxiliary valve 40 associated with each of said regulating valves for controlling said lighter, a single control element for each of said regulating valves and its associated auxiliary valve, and means responsive to initial movement of each control element for 45 operating said associated auxiliary valve and responsive to further movement thereof to operate the associated regulating valve.

4. The combination of a plurality of gas burners including a remote burner, individual valves including a remote burner valve for controlling the admission of gas to each of said burners, a lighter positioned between said burners for projecting igniting flames toward said burners, gas communications between said valves 50 and lighter, a torch connected with said remote burner valve and lying in the path of one of said igniting flames, means responsive to operation of said remote burner valves to supply gas to said torch, said torch projecting an igniting flame 55 picked up from said lighter flame and projecting the same toward the remote burner, means responsive to the initial rotation of said remote burner valve to render said lighter effective, means for supplying gas to said remote burner 60 while said torch is supplied with gas and means for cutting off the gas supply to said torch when 65 said remote burner is lit.
